UNITED STATES PATENT OFFICE

2,419,071

ELECTROMAGNET

Chester I. Hall, Vischer's Ferry, N. Y., assignor
to General Electric Company, a corporation of
New York

Application May 2, 1944, Serial No. 533,888

3 Claims. (Cl. 175—336)

1
My invention relates to electromagnets, more particularly to direct current electromagnets, and has for its object a simple, reliable and light weight electromagnet of this type.

In carrying out my invention in one form I provide an operating electromagnet having an operating coil of low inductance coefficient and a pivotal mounting for the armature of the magnet including a grommet made of a resilient material, such as rubber, by means of which the armature is secured at one end to the magnet frame. I also provide a relatively long flexible spring having one end secured to the armature and carrying on its other end a movable contact. This elongated spring gives a more gradual build-up of pressure between the contacts after they engage each other and thereby tends to obviate bouncing of the movable contact and arcing resulting therefrom.

For a more complete understanding of my invention reference should be had to the drawing in which Fig. 1 is a perspective view of a contactor embodying my invention; Fig. 2 is a fragmentary side elevation view of the device of Fig. 1; Fig. 3 is a fragmentary view in section of a resilient mounting for one end of the armature; Fig. 4 is a view in section of a resilient armature support; Fig. 5 is an elevation view of the two halves of an interlock switch mounted on the contactor, while Fig. 6 is a side elevation view of the interlock switch of Fig. 5 with a part broken away to show the interior.

Referring to the drawing, in one form of my invention I provide a suitable supporting base or panel 10 made of electrical insulating material on which the operating electromagnet and the stationary contact (not shown) with its arc chute 11 are mounted.

The electromagnet comprises a coil 12 whose diameter is substantially greater than its axial length, preferably several times greater than its length as shown in the drawing for the purpose of obtaining high speed of operation in both closing and opening of the contactor. The magnet core comprises a plate 13 made of magnet iron secured to the support 10 by suitable screws or bolts and having its lower end as seen in the drawing provided with a transversely extending portion 14 projecting outward from the support 10 to a point just beyond the outer limits of the coil. On this portion 14 are two brackets 15 (only one of which is shown in the drawing) to which the lower end of the armature 16 comprising a plate of magnet iron is secured by means of two grommet-like members 17 and 18 made of

a resilient material and bolts 19 and 20 extending through the grommets and the bracket 15. The members 17 and 18 are made of a suitable rubber or rubber-like material, preferably neoprene.

2
As shown in the drawing, the lower end of the armature has a width which is about the same as the diameter of the coil and the two supports 17 and 18 are secured in spaced-apart apertures 5 in its lower end. As shown in Fig. 4, the grommet 17, and also the grommet 18, are provided with a central hole 21 for the bolt 19 in a cylindrical portion 22 which extends through a hole 23 (Fig. 3) in the end supporting portion of the armature and preferably is slightly larger than the hole so as to secure itself permanently therein. Also, the two circular flanges 24 and 25 of the grommet are formed with their outer edges closely spaced together as shown in Fig. 4, while at 10 the point where they join, the cylindrical portion 22, they are spaced apart a distance substantially equal to the thickness of the armature 16. Thus, when the grommet is forced part way through the hole so that the cylindrical portion 15 lies in the hole, the flanges of the grommet are spread apart as shown in Fig. 3 by the armature between them and thereby by reason of their resiliency grip the armature between them and secure the grommet to the armature. This construction will exclude dust and foreign matter. The bolts 19 and 20 are drawn up tightly thereby to compress somewhat the grommets and secure the armature to the bracket 15.

As shown, the bracket extends downward at 35 an angle somewhat less than 90 degrees with the core portion 14 whereby the armature is caused to extend normally in non-parallel relation upwardly with respect to the plate 13 which position is the unattracted position of the armature. 40 The armature is thus biased to this position by the resiliency of the rubber supporting grommets. It is additionally biased by means of a helical spring 26 surrounding a supporting bolt 27 secured to the core portion 14 and bearing 45 against an arm 28 secured to the lower end of the armature by a screw 28a and preferably also by a welded connection. When the coil 12 is energized the armature 16 moves to its attracted position about a pivot substantially at right angles to the bolts 19 and 20 and passing through 50 the bolts, the rubber members 17 and 18 being flexed and compressed to provide for this pivotal movement.

Preferably as shown, the armature 16 carries 55 a cylindrical core portion 29 having a length

substantially one half the axial length of the coil and having its inner end engaging, when attracted by energization of the coil, the end of a complementary cylindrical core portion 29a in the coil secured to the plate 13. This type of magnetic circuit has a very low magnetic leakage factor resulting in better magnetic efficiency and higher speed. I have found that the pancake shaped magnet coil has a distinct advantage in the operation of the contactor in that the coil provides a much quicker build-up of magnetic force when the coil is connected to a suitable direct current source of supply, and therefore much quicker pick-up of the armature. Also, as compared with an equivalent conventional coil having a length considerably greater than its diameter, a typical coil of this shape had appreciably less copper in its winding.

I have also provided a relatively long flexible strip spring 30 on the upper end of which is secured a movable contact 31. This spring has its lower end extending downward to a point near the lower end of the armature where it is provided with a short lateral portion 31a which rests against the armature 16, preferably in a groove provided for it in the armature. When the armature 16 is in its unattracted position, the spring extends upwardly in substantially parallel relation with the armature and at its upper end rests against a bracket 32 extending cross-wise with respect to the spring and the armature and having its ends secured to the armature by screws 33 and 34.

The bracket 32 provides an adjustment for the upper end of the spring with respect to the armature whereby the spacing of the movable contact from the stationary contact can be adjusted as desired. Thus, by inserting a washer of suitable thickness between each end of the bracket 32 and the armature, after which the screws 33 and 34 are tightened, the upper end of the contact 31 is given the desired contact wipe. The open position or air gap is adjusted by nuts 41.

Another adjustment of the spring 30 for varying the force of the spring is provided by means of a screw 35 extending through an aperture in its lower end. Thus by turning this screw against the spring, it is bent toward the armature and the force of the spring available for contact pressure thereby reduced. The screw is held in adjusted position by means of a lock member 36 having an aperture fitting over the head of the screw and having its lower end secured to the armature by the screw 28a.

When the armature moves toward its attracted position upon energization of the coil, the movable contact 31 engages the stationary contact at some predetermined point in the movement of the armature and before the armature reaches its fully attracted position. Thereafter the armature continues its movement to its attracted position and thereby applies a desired force through the spring 30 to the movable contact 31 and also wipes the movable contact over the stationary contact. After engagement of the movable contact with the stationary contact, the armature and bracket 32 continue their movement and move away from the spring 30 which is thereby bent and caused to apply an increasing pressure to the stationary contact. The spring, by reason of its length, provides for a gradual increase in the pressure applied to the movable contact after its engagement with the stationary contact. This gradual application of pressure is an advantage in preventing bouncing

of the movable contact and consequent arcing between the contacts during the closing movement.

At its upper end the armature is forked to provide two projections 38 and 39 which can be utilized to operate suitable interlock switches only one of which, 40, is shown. Stops for limiting the movement of the armature to its unattracted position are provided consisting of two bolts extending through the two portions 36 and 38 only one of which, 41, is shown, and provided with adjustable heads against which the portions rest when the armature is in its unattracted position.

The interlock switch 40, which is described and claimed in my divisional application Serial No. 598,881, filed June 8, 1945, comprises two casing parts 42 and 43 (Fig. 5) made of a molded electrically insulating material which are identical in construction and which fit together in reversed end relation with each other. As shown, these parts 42 and 43 are provided with registering cavities and have portions 44 and 45 respectively at their ends having thicknesses substantially equal to the combined thickness of the remaining portions of the two parts when they are put together. These portions, as indicated in Fig. 4, are at opposite ends of the two assembled parts, i. e., the casing formed by the two parts. The thick portions have molded in them stationary switch members 46 and 47 each of which has switch contacts on each side.

Also, each of the two members is provided with semicircular depressions or grooves 48 and 49 which when the parts are put together form apertures for a longitudinally movable switch member or plunger 50 extending in a direction at right angles to the stationary contact faces on the members 46 and 47. The plunger 50, which is made of a molded electrically insulating material, extends through an aperture in an electrically conducting contact bridging member 51 normally biased by a helical spring 52 toward the right-hand, as seen in Fig. 4, against a flange 53 on the plunger. The other end of the spring rests against a flange 54 secured to the plunger. On the opposite side of the flange 54 is a helical spring 55 whose other end surrounds a short tubular spring seat 56 on a member 57. This member 57 is provided with an aperture concentric with the spring seat 56 through which the plunger extends and the member 57 fits in a recess 58 provided for it in each of the two halves.

Thus, when the two parts, as shown in Fig. 5, are folded over on each other, the bridging member 51 cooperates with the contacts on one side of each of the members 46 and 47 and is biased against the contacts by the spring 52. This forms a normally closed interlock switch. The switch 40 is secured to the support 10 by terminal bolts 59 and 60 molded in the casings and connected electrically to the members 46 and 47 with the plunger 50 in position to be engaged by the projection 38 or 39 when the armature is moved to its attracted position whereby the switch is opened.

As shown in Fig. 6, the interlock switch can be converted easily into a normally open switch by simply reversing the bridging member 51. The bridging member has its ends bent into laterally displaced relation with the central portion secured to the plunger 50, these ends being on the left-hand of this central portion as seen in Fig. 4. With the bridging member reversed to the position shown in Fig. 5, it is turned through an angle

of 180 degrees about an axis perpendicular to the plunger 50. The bridging member is held by the spring 55 in spaced relation with the stationary contacts. Also, the bridging member is positioned as seen in Fig. 5 on the right-hand side of the flange 53 as is also the spring 52. The flange 53, and also flange 54, preferably is a metal part provided with a slot into which fits a portion of reduced size on the plunger whereby the flanges can be readily removed for disassembly of the parts when the two halves of the casing are separate.

A flexible electric conductor 61 forms an electric connection between the contact 31 and a terminal member 62 secured to the base 10.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. An electromagnet comprising an operating coil, a magnet core member for said coil, an armature for said coil including a supporting portion provided with a hole, a member made of resilient material extending through said hole and provided with flanges on opposite sides of said supporting portion constructed and arranged to grip said supporting portion between them, said resilient member being provided with a central aperture, a support for said armature, and a bolt member secured to said support extending through said aperture for compressing said resilient member against said support thereby to secure said resilient member and said armature to said support so that said armature is biased by said resilient member to its unattracted position away from said coil, said resilient member flexing upon energization of said coil to provide for movement of said armature to its attracted position about an axis substantially at right angles to said bolt member.

2. An electromagnet comprising an operating coil, a magnet core for said coil, a transversely extending projection on said magnet core, an armature member having a supporting portion provided with a hole in one end, a resilient member made of rubber-like material extending through said hole and provided with two flanges on op-

posite sides of said armature constructed and arranged to grip said armature between them, said resilient member being provided with a central aperture, a bolt extending through said aperture and secured to said projection compressing said resilient member against said projection whereby said armature is secured to said projection and biased by said resilient member to its unattracted position away from said coil, said resilient member flexing upon energization of said coil to provide for movement of said armature to its attracted position about an axis substantially at right angles to said bolt.

3. An electromagnet comprising an operating coil, a magnet core for said coil, transversely extending projections on said magnet core, an armature member provided with two holes in one end, a member made of resilient material extending through each of said holes and provided with two flanges on opposite sides of said armature constructed and arranged to grip said armature between them, each of said resilient members being provided with a central aperture, a bolt extending through each of said apertures and secured to one of said projections, said bolts being provided with heads for compressing said resilient members against said projections whereby said armature is secured to said projections, said projections and said resilient members being constructed and arranged to bias said armature to its unattracted position away from said coil, said resilient members flexing upon energization of said coil to provide for movement of said armature to its attracted position about an axis substantially at right angles to said bolt.
